The ornamental design for a handle and cap assembly for the print head of imprinting machines, substantially as shown and described.

DESCRIPTION

FIG. 1 is a perspective view of a handle and cap assembly for the print head of imprinting machines, embodying my new design;

FIG. 2 is a top plan view thereof;

FIG. 3 is a side elevation view thereof, viewed from below FIG. 2, the opposite side elevation being the mirror image thereof;

FIG. 4 is an end elevation view thereof, viewed from the left of FIG. 2, the opposite end elevation being the mirror image thereof; and

FIG. 5 is a bottom view thereof.
